UNITED STATES PATENT OFFICE.

LEE P. HYNES AND HARRY A. WILLIAMS, OF ALBANY, NEW YORK, ASSIGNORS TO HYNES & COX ELECTRIC CORPORATION, OF ALBANY, NEW YORK, A CORPORATION OF NEW YORK.

THERMOSTAT.

Application filed January 8, 1926. Serial No. 80,046.

For a detailed description of the present form of our invention, reference may be had to the following specification and to the accompanying drawing forming a part thereof, wherein

Fig. 1 is a side elevation of our device;

Fig. 2 is a plan thereof;

Fig. 3 illustrates the heat-responsive element, and

Fig. 4 shows the electric contact.

Our invention relates to a thermostat of the type wherein a compound strip of metal automatically bends as it becomes heated, due to unequal expansion of the component metals and thus controls an electric circuit. We employ a narrow rectangular strip of this type and confine it between two immovable end-stops, and add a third stop on one side at or near the middle which may also serve as the electric contact. The end stops are so adjusted that at a given normal temperature the strip will press firmly against the side stop and thereby close the electric circuit. As the strip begins to heat, its first tendency is to arch as a whole because of the unequal expansion of the two metals, thereby pressing more firmly against the side stop. Since the side stop is immovable, the two halves of the strip thus begin to arch independently of each other as the temperature increases until the two lines of thrust from the respective end-stops towards the center pass the dead center relation to each other. Then the strip snaps away from the side stop and breaks the circuit. When the temperature drops again the strip returns to its initial position, also with a snap.

Referring to the drawing, 1 represents a rigid base plate having at its respective ends the two upright portions A and B. On the inside of upright A is a horizontal V-groove, and through upright B passes a screw 4 having a socket-like inner end and secured at the desired point of adjustment by a set screw 6. In the bottom of the base is a screw 5 which serves as a back-stop for the strip and is locked by another set screw 6.

The compound strip 3 shown in Fig. 3, is held at its two ends by the respective uprights A and B acting as immovable stops therefor. The strip is provided, at its left end, with two shoulders filed to a knife edge and adapted to fit into the V-groove on upright A. Between the two shoulders is a

pointed projection that enters a recess in the bottom of the groove to prevent sidewise escape of the strip from the groove. The right-hand end of the strip has a similar pointed projection, the tip end of which is formed into a small cylindrical ball that is received in the end socket of screw 4. Near the middle of the strip is a rivet 9 (see Fig. 4) insulated therefrom by mica washers 17 and an insulating bushing 12. The lower end of the rivet 9 is headed over against a bronze washer 11 and on its upper end is a loose contact disc 8 of silver. The slight play of this disc is limited by a flange on the washer below it and the headed end of the rivet above it. Extending across the uprights A and B and seated thereon is a sheet-metal channel-shaped bar 2 (see Fig. 2) through the bottom of which project two insulated contacts 10 that are engaged by the silver disc 8 and serve as an immovable side-stop for the strip. The channel-bar 2 is secured at one end to upright A by rivets 16 and at the other end is adjustably secured to upright B by a screw 20. The line wires 18 connect with the said contacts 10 respectively and pass out at one end of the channel 2 under a clamp 19.

In operation the set of strip 3 is so adjusted that at normal temperature, the disc 8 will bear against contacts 10 with sufficient force to close the circuit from one contact to the other, the silver disc 8 bridging the gap between them. The contacts 10 also serve to stop any upward movement of the strip at that point. Between contacts 10 and the two ends of the strip there is no side stop so that each half of the strip can arch independently as it will. At a definite higher point of temperature the direction of the counterthrust from the respective ends of the strip towards the center will become such that the strip will spring away from contacts 10 and against back-stop 5 thereby opening the circuit.

What we claim as new and desire to secure by Letters Patent is:

1. A thermostat comprising a heat-responsive strip with fixed end stops therefor and a distorting side stop for producing local lateral movement of the strip at a predetermined temperature.

2. A thermostat comprising a heat-responsive metallic strip, with fixed end stops and

a distorting side stop therefor at an intermediate point of the strip for producing local lateral movement of the strip at a predetermined temperature.

5. 3. A thermostat comprising a heat-responsive metallic strip, a base having two end stops for the strip one having a knife edge engagement with the strip and an intermediate distorting side stop for producing local lateral movement of the strip at a predetermined temperature.

10. 4. A thermostat comprising a base having offset stops, a heat-responsive metallic strip held under stress between said stops, a side

15. stop at an intermediate point of said strip in position to limit the lateral movement of the strip at that point leaving the strips free to respond locally between the side-stop and the two end stops and an electric circuit

controlled by lateral movement of the strip. 20

5. A metal thermostat comprising a base, a heat-responsive strip having end stops on the said base, a bridging member extending between said stops, and a side stop for the strip mounted on said member at an intermediate point thereof. 25

6. A metal thermostat comprising a base, a parallel heat-responsive strip having end-stops on said base, a channel-shape bridging member extending between said stops, a side stop for the strip serving also as an electric circuit-closer, and circuit wires in said channel. 30

Signed at Albany, county of Albany, State of New York, this 31st day of December, 35
1925.
